UNITED STATES PATENT OFFICE.

LOUIS E. ALLYN, OF PEKIN, ILLINOIS, ASSIGNOR TO AMERICAN CAR AND FOUNDRY CO., OF NEW YORK, N. Y., A CORPORATION OF NEW JERSEY.

TANK-CAR.

1,170,864.

Specification of Letters Patent.

Patented Feb. 8, 1916.

Application filed April 6, 1910. Serial No. 553,782.

To all whom it may concern:

Be it known that I, LOUIS E. ALLYN, a citizen of the United States, residing at Pekin, in the county of Tazewell and State of Illinois, have invented certain new and useful Improvements in Tank-Cars, of which the following is a specification.

My invention relates to tank cars, and particularly to means for anchoring the tank upon a car underframe, and to means of connection therebetween to permit limited longitudinal movement thereof and to facilitate a ready detachment of the tank from the underframe.

15 In the drawings, Figure 1 is a side elevation showing a portion of a tank and an underframe with my device attached; Fig. 2 is a plan view of my device; Fig. 3 is a vertical sectional view on the line 3—3 of Fig. 2; Fig. 4 is a vertical sectional view through the line 4—4 of Fig. 2, and Fig. 5 is a detail view of a follower board.

In the drawings, A are parallel channel-beams longitudinally disposed with reference to the ordinary car trucks and are adapted to be suitably supported upon said trucks and are provided with a series of slots a.

B is a tank and C is a plate adapted to be riveted to the bottom thereof, provided with shoulder portions D adapted to be seated upon channel-beams A, the said plate being also provided with a portion E adapted to depend between the channel-beams A, said depending portion being equipped with strengthening ribs F, as best seen in Figs. 3 and 4 and also provided with slots f in each of the walls thereof adapted to carry the anchoring keys.

0 The depending portion E is adapted to be detachably interlocked with the channel-beams of the underframe by means of keys O and O' passing through slots or key-ways a in said channel-beams, said slots or key-ways being cut through the neutral axis of said channel beams, that is, in the part of the web of such beams which will be neutral, or will be under neither tension nor compression when the beam has a tendency 5 to bend, said slots being of considerably greater length than the width of the keys, said keys being held in a substantially fixed relation with depending portion E, thus adapting the tank to be moved backwardly

and forwardly upon the underframe within 55 the limits of the length of the slots a.

For the purpose of limiting the movement of the tank upon the channel-beams, abutment blocks G and G' are provided which are supported between the channel-beams by 60 means of keys, the one indicated as L being designed to support block G and the one designated as L' supporting block G'.

H and H' are abutment blocks bearing respectively against the end walls of depending portion E, said blocks being supported, block H by means of key N and block H' by means of key N', and I have interposed coil springs M between blocks G and H, supporting the same upon studs g and g' located 70 respectively upon blocks G and H, and spring M' between blocks G' and H' and said springs M' are supported upon studs g² and g³ respectively upon blocks H' and G'. The keys L and L', and N and N' are 75 passed through the slots a in the channel beams, there being corresponding slots in both beams, and said slots being substantially about two-thirds the length of slots a which carry the keys O and O'. 80

For the purpose of distributing the stresses on the cushioning springs upon the springs attending the movement of the tank in either direction of its movement, I have provided the follower boards K, which said 85 boards are provided with slots as l l', which are of size just sufficient to permit keys O O' to be passed therethrough. The connection of the follower boards with the keys O and O' will cause said boards to be moved with 90 the depending portion E. The normal relation of the keys with reference to the follower board is as disclosed in Fig. 1, in which figure keys L and L' occupy positions at opposite outward extremities of follower 95 board slots k, k' and keys N and N' at the extreme limits of the slots i, i' nearest depending portion E. The keys occupying the position relative to the slots in the follower board as indicated in Figs. 1, 2, and 4, then 100 when the tank is moved to the right, the depending portion E abutting with block H' will cause spring M to be compressed against the stationary block G' and the slot k' in the follower board will permit the board to be 105 moved to the limit of the slot, through which said key is passed, and key N' will pass forwardly in the direction of movement

of the tank resting in slot i' , and during such movement the follower board will cause key L to draw block G forwardly against spring M, thereby dividing the strain upon springs M and M'. A reverse movement of the tank will carry with it simply a reversal of the operation above described, effecting the same result.

With reference to the support of the tank upon the underframe it will be observed that the shoulders D bear upon the upper faces of the flanges of the channel-beams, providing a support upon which the shoulders and tank are readily slidable. The portion E depending from plate C has a lateral bearing contact with the follower boards K, which supports the tank against lateral thrust and serves as an aid to shoulders D in preventing the tank from turning. The keys connecting the underframe to the tank will render the latter readily detachable from the former and serves to prevent vertical jumping of the tank upon the frame, and also in conjunction with the bearing of the shoulders D upon the upper faces of the channel-beams, prevents longitudinal rocking.

I have shown one form of embodiment of my invention but other forms may be employed without departing from the spirit thereof.

Cutting the key-ways for the keys through the neutral axis of the sills is a decided advantage over cutting such key-ways in either that part of the sills subjected to stresses of tension or compression, as, in any other location than in the neutral axis, the key-ways will become a decided source of weakness to the structure comprising such sills.

40 What I claim is:

1. In a tank car, a pair of sills, a tank provided with a portion depending between the sills, a pair of movable stop blocks on each side of the depending portion, resilient members interposed between each pair of stop blocks, and means for connecting the depending portion and the stop blocks in a relation that a longitudinal movement of the tank in either direction will cause a corresponding compression of both the resilient members.

2. In a tank car, a pair of sills, provided with a plurality of longitudinal slots therein, a tank provided with a portion depending between the sills, a pair of stop blocks on each side of the depending portion, springs interposed between each pair of stop blocks, follower boards interposed between the sills and the depending portion and stop blocks, bars connecting the depending portion, the follower boards and the sills in a relation that the longitudinal movement of the depending portion will carry with it the follower boards, and bars connecting the stop blocks, the follower boards and the sills

in a relatively movable relation, whereby when the tank is shifted in either direction through the follower boards, the stop blocks rearwardly of the direction of movement will be carried forwardly with the depending portion, causing a corresponding compression of both of the springs.

3. A car structure including a tank; a supporting structure therefor upon which the tank may move longitudinally with respect to the supporting structure; a connection taking part in holding the tank down and which is attached to the tank and is moved by the tank upon and longitudinally of the supporting structure; and means for preventing vertical movement between said connection and the tank supporting structure without preventing longitudinal movement of said tank and connection.

4. A car structure including a tank; a supporting structure therefor upon which the tank may move longitudinally with respect to the supporting structure; a connection taking part in holding the tank down and which is attached to the tank and caused to slide by the tank upon the supporting structure; and means for preventing vertical movement between said connection and the tank supporting structure without preventing longitudinal movement of the tank and said connection.

5. A car structure including a tank; a supporting structure therefor upon which the tank may move longitudinally with respect to the supporting structure; a connection taking part in holding the tank down and which is attached to the tank and is caused to slide by the tank upon and longitudinally of the supporting structure; and means for preventing vertical movement between said connection and the tank supporting structure without preventing longitudinal movement of the tank and connection.

6. In a tank car, spaced sills, a tank above said sills, an anchor member depending from said tank between said sills, means connecting the tank and sills in slidable relation, spaced cushioning means adapted to contact with each end of said anchor member, and means connecting said spaced cushions.

7. In a tank car, spaced sills, a tank above said sills, an anchor member depending from said tank between said sills, means connecting the tank and sills in slidable relation, spaced cushioning means adapted to contact with each end of said anchor member, and means interposed between said sills and said anchor member connecting said spaced cushions with said anchor member.

8. In a tank car, longitudinally slotted spaced center sills, a tank movable with relation thereto, an anchor member connected to said tank and depending between said sills, keys passing through said anchor mem-

ber and slots in said sills and held in substantially fixed relation with said anchor member, and cushioning means connected with said sills in alignment with said anchoring member longitudinally of said sills.

9. In a tank car, spaced sills, a tank movable relative to said sills, a tank anchor depending below the top of said sills, cushioning means at each end of said anchor, and means connecting said cushioning means adapted to cause conjoint action thereof during movement of said tank.

10. Means for anchoring a tank to an un-

derframe, comprising spaced cushioning means for said tank, means connecting the tank and underframe respectively to parts of said cushioning means and means for connecting the parts of the cushioning means connected with the underframe.

In testimony whereof I have affixed my signature in presence of two witnesses.
